UNITED STATES PATENT OFFICE

PATRICK FARRELLY, OF SAN FRANCISCO, CALIFORNIA

COLLAR SHAPER

Application filed February 11, 1931. Serial No. 515,000.

This invention relates to a collar shaper and more particularly to a device for shaping the collar of a new or freshly laundered shirt of the type having a collar portion permanently attached.

It is common practice in the laundering of shirts with attached collars to iron the collar and often the cuffs of the shirt in a machine provided for that specific purpose and to press the remainder of the shirt in a machine known as a bosom press. The collar of a shirt which has been handled in this manner, while it may be very neatly ironed, does not lie flat against the shirt, but stands up, assuming a more or less oval shape. Consequently, the collar cannot be folded with the shirt into the customary flat package for delivery without considerable difficulty.

It is, therefore, the object of the present invention to provide mechanical means for shaping the collar of the shirt neatly and quickly, and further, for maintaining engagement with the collar while the shirt is being folded, thus expediting the entire folding operation.

One form that the invention may assume is exemplified in the accompanying drawings and following specification, in which further objects and advantages will be apparent.

In the drawings—

Fig. 1 is a front elevation of a collar folder embodying my invention.

Fig. 2 is a view similar to that shown in Fig. 1 showing the parts of the collar folder in the positions they assume while a shirt is being placed on it.

Fig. 3 is a perspective view of the collar folder and a shirt being placed on it.

Fig. 4 is a sectional view taken on the line IV-IV of Fig. 1.

Fig. 5 is a plan view of the device as shown in Fig. 1.

Referring more particularly to the drawings and especially to the views shown in Figs. 1, 2, and 4, I show a vertically disposed supporting plate 10 secured to one end of a folding table, generally indicated at 11 in Fig. 4. Disposed adjacent the vertical supporting plate 10 are a pair of vertically disposed and parallel bars 12 and 13. A pair

of links 14 and 15 are pivotally secured as at 16 to the supporting plate and pivotally secured as at 17 and 18, respectively, to the bars 12 and 13. Similarly, links 19 and 20 are pivotally secured to the plate 10 at 21 and pivotally connected at 22 and 23 respectively, to the bars 12 and 13. By means of these connections the bars 12 and 13 are free to move upwardly and toward each other, being maintained in parallelism and guided in such movement by the links 14, 15, 19 and 20.

A spring 24 is carried by the pivot 16 and is secured at its ends to the pivots 17 and 18, and urges the bars 12 and 13 outwardly and downwardly. A similar spring 25 may be employed if desired in connection with the links 19 and 20, as shown. Downward and outward movement of the bars 12 and 13 is limited by blocks 26 and 27 secured to the plate 10. Upward and inward movement of the bars 12 and 13 is accomplished by means of the following mechanism.

A bell crank 28 is pivotally connected to the plate 10 at 29 and also pivoted at 30 to the bar 13 so that downward movement of the arm 31 of the bell crank will cause the bar 13 to move upwardly and inwardly. In order to impart similar movement to the bar 12, a gear 32 secured with relation to the bell crank 28 is in mesh with a gear 33 rotatably mounted on the plate 10. The gear 33 carries an arm 34 pivotally connected as at 35 to the bar 12. Thus, downward movement of the arm 31 not only imparts motion to the bar 13 but through the gears 32 and 33 and the bar 34, causes the bar 12 to move upwardly and inwardly. The position assumed by the bars upon downward motion of the arm 31 is illustrated in Fig. 2.

Any suitable means may be employed for actuating the bell crank in the manner described and I have shown for purposes of illustration a foot pedal 36 connected by means of a spring wire 37, guided in a flexible cable 38, to the arm 31, whereby downward pressure upon the pedal 36 will impart downward movement to the arm 31 and cause the above described motion of the bars.

Connected to the upper ends of the bars 12 and 13 are a pair of fingers 37 and 38 formed

on an angle so as to overlie one end of the top of the folding table. These fingers are provided with outwardly flared edges 39 so that when they are brought together they assume a wedge like or tapered shape and are removably connected, as by screws 40, to the bars 12 and 13, so that they may be quickly and conveniently replaced in case of breakage.

The operation of the device is illustrated in

- 10 Figs. 3 and 5. Referring to Fig. 3 a protective housing 41 is shown as enclosing the greater part of the mechanism above described and the fingers 37 and 38 are illustrated in the position assumed by them when the pedal 15 36 has been depressed. When the fingers are in this position the collar portion of a shirt is slipped over their ends as shown, and the pedal is then released to permit the fingers to move downwardly and apart, as shown in 20 Fig. 5. This downward and outward movement of the fingers 37 and 38 causes the collar of the shirt to be spread and flattened and the operator may then by exerting a slight pull on the tail portion of the shirt, cause the collar 25 to be firmly engaged by the tapered edges 39 of the fingers. The shirt in this position is ready for folding and the conventional cardboard stiffener may be applied if desired.

During the folding operation the fingers 37 30 and 38 serve to hold the shirt firmly at one end, thus dispensing with the necessity of the usual holding devices employed for this purpose.

While I have shown the collar shaper attached to the extreme end of the folding table, it should be understood that a portion of the table may be notched or recessed if desired so that the operating mechanism does not extend outwardly beyond its end, or the 40 mechanism may be mounted beneath the table and the fingers may extend upwardly through a slot suitably formed in the top of the table at any desirable position. When the device is mounted as shown, I employ a guide bar 42 45 to prevent movement of the fingers away from the supporting plate 10.

While I have shown a preferred embodiment of my invention, it should be understood that various changes may be resorted 50 to in the arrangement and construction of its several parts without departing from the spirit and scope of the appended claims.

Having thus described my invention, what I claim and desire to secure by Letters Patent 55 is:—

1. In a device for shaping shirt collars, a pair of flat fingers adapted to overlie a folding table in a plane parallel to the top thereof, means normally urging said fingers downwardly and apart, and means for causing said fingers to move upwardly and toward each other.

2. In a device for shaping shirt collars, a pair of flat fingers adapted to overlie a folding table in a plane parallel to the top thereof,

means normally urging said fingers downwardly and apart, means limiting their downward movement, and means for causing said fingers to move upwardly and toward each other.

3. A device of the character described comprising a pair of relatively flat co-planar finger members, tapered outer edges on said finger members, means for causing said finger members to move upwardly and toward each other, and means normally urging said finger members to move downwardly and away from each other.

4. A device of the character described comprising a pair of relatively flat parallel finger members disposed in spaced relation, means normally urging said members apart, and means operable to bring said members together, said fingers having tapered outer edges to form a wedge-shaped support for a shirt collar.

5. A device of the character described comprising a pair of relatively flat finger members, means normally urging said finger members apart, and means for causing said finger members to move toward each other, said finger members having their outer edges disposed at diverging angles to prevent the removal of a collar therefrom while they are urged apart.

6. The combination with a shirt folding table of a device for shaping and maintaining engagement with the collar of a shirt, said device comprising a pair of parallel flat fingers around which the collar may be positioned, and means for separating said fingers to shape and engage the collar.

7. A collar shaping device of the character described comprising a pair of fingers, a pair of bars supporting said fingers, links pivotally engaging the bars and pivotally secured to a stationary support, and means for imparting movement of said bars about the pivotal support for said links.

8. A collar folding device of the character described comprising a pair of fingers, a pair of bars supporting said fingers, link members pivotally secured to said bars and to fixed points adjacent the bars for maintaining the bars parallel, and means for causing the bars to move toward each other on their pivotal supports.

9. A collar shaper of the character described, comprising a pair of relatively flat, elongated finger members arranged parallel to each other insertable in the collar of a shirt and means for urging said finger members apart to assume a spaced position to engage opposite sides of the collar and cause it to assume a flat position.

10. A collar shaper of the character described, comprising a pair of relatively flat, substantially parallel elongated finger members insertable in the collar of a shirt and

means for urging said finger members apart to assume a spaced co-planar position to engage opposite sides of the collar and cause it to assume a flat position, said finger members having tapered outer edges to retain the collar against removal therefrom while they are urged apart.
